TUYÈRE DAMPER

Herbert E. Preston, Philadelphia, Pa., assignor
to American Engineering Company, Philadel-
phia, Pa., a corporation of Pennsylvania

Application March 21, 1928, Serial No. 263,318

10 Claims. (Cl. 110—44)

My invention relates to stokers, and it has for one object the provision of simple and efficient air-control means therefor.

Another object of my invention is to provide 5 stoker air-control means that is particularly applicable to relatively long stokers.

Still another object of my invention is to provide 10 air-control means for the tuyère chamber of a stoker, permitting a variable air supply to different portions of the tuyère chamber. Such control is desirable in long stokers, more especially, those having low boiler ratings, since it permits the control of the air supply over the entire fuel bed, with resulting increased efficiency in furnace 15 combustion conditions.

A further object of my invention is to provide 20 stoker apparatus comprising a tuyère chamber, a plurality of tuyères mounted on one side of the chamber, and a plurality of pivoted damper elements constituting at least a portion of another side of the tuyère chamber, whereby the air supply 25 to the tuyère chamber may be controlled.

A still further object of my invention is to provide 30 air-control apparatus of the character described having manually-adjustable means so positioned that approximately one-half of the dampers may be controlled from one side of the furnace and the other half from the other side.

With these and other objects and applications 35 in mind, my invention further consists in the details of construction and operation and arrangement, hereinafter described and claimed and illustrated in the accompanying drawings, wherein

Fig. 1 is a longitudinal sectional view of a furnace embodying my invention, the sectional plane being taken on the line 1—1 of Fig. 3;

Fig. 2 is a partial bottom-plan view of the 40 stoker of Fig. 1;

Fig. 3 is a transverse sectional view through one 45 of the tuyère chambers, the sectional plane being taken on the line 3—3 of Fig. 1;

Fig. 4 is a detail, vertical sectional view through one of the side walls of the furnace and adjacent stoker portions, with certain of the stoker details omitted, the sectional plane being taken on the line 4—4 of Fig. 1;

Fig. 5 is a similar view through the opposite furnace side wall;

Fig. 6 is a vertical sectional view similar to 50 Figs. 4 and 5, showing the mounting of the damper operating shafts in the central portion of the stoker;

Figs. 7 and 8 are perspective views of one of 55 the damper plates of Fig. 1, looking respectively from the top and bottom thereof;

Fig. 9 is an enlarged detail view of one of the exteriorly mounted supporting stands for the damper operating hand-wheels, a portion of one of the stands being broken away to illustrate the indicating mechanism;

Fig. 10 is a vertical sectional view taken on the line 10—10 of Fig. 9; and

Figs. 11 and 12 are enlarged detail, side and end elevational views of the damper actuating shafts and the exteriorly positioned stands.

The relatively short stokers now in use have functioned satisfactorily with air-control means of the single damper type. Such air-control means, however, is not adaptable to the stoker described in my co-pending application Serial 15 No. 263,900, filed March 22, 1928, and assigned to the American Engineering Company, which is characterized, among other things, by its extremely long length. As a result, in order to obtain efficient combustion in the furnace, it has 20 been necessary to develop an entirely new form of air-control, wherein a relatively variable air supply is afforded the different portions of the furnace.

One solution of the problem is shown in the 25 drawings, wherein a furnace 1 is provided with an inclined, multiple-retort stoker 2 of the under-feed, forced-draft type. The stoker 2 extends from a front wall 3 rearwardly and downwardly, and it comprises a plurality of series of inclined 30 tuyère chambers or boxes 4 and a corresponding plurality of series of retorts 5, alternating therewith. A sufficient number of series of tuyère chambers 4 and retorts 5 is provided to extend across the width of the furnace 1, between side 35 walls 6 and 7.

In accordance with my invention, each tuyère box 4 comprises a pair of relatively wide, spaced, steel side-plates 8 and 9 which extend rearwardly and downwardly from supporting plates 11 40 which are anchored in the furnace front wall 3. The steel plate 9 also constitutes a side wall for the adjacent retort 5, while the opposite steel plate 8 also serves as a side wall for the next adjacent retort 5, as shown in Fig. 2. A series of 45 tuyères 12 are positioned to form an upper side 13 of each tuyère chamber 4, being removably mounted on cast-iron plates 14 detachably secured to upper edge portions 15 of the steel side plates by bolts 16. The tuyères 12 are mounted 50 on the detachable cast-iron plates 14, rather than directly on the steel side plates 8 and 9, inasmuch as the upper side 13 of the tuyère box is subjected to intense heat, with resulting rapid deterioration or burning of the tuyère supporting 55

means. Should any one portion of the tuyère supporting means be damaged by the excessive heat, it is only necessary to replace one or more cast-iron supporting plates 14, leaving the remaining supporting plates 14 as well as the main supporting side plates 8 and 9 undisturbed.

Inasmuch as combustion occurs in the furnace in approximately three zones, that is, a front zone 17, wherein the coal loses its moisture content and volatile matter; an intermediate zone 18, wherein combustion is most active; and a rear zone 19, wherein combustion is less rapid and the fuel bed becomes thinner; I provide means whereby correspondingly positioned groups of tuyères 21, 22 and 23 which together constitute each series of tuyères, may be supplied with relatively variable amounts of air. To this end, each of the tuyère chambers 4 is transversely divided, by means of cross plate members 24, 25 and 26, which extend between the steel side plates 8 and 9, into a plurality of chamber portions 27, 28 and 29 which are in operative relation to the tuyère groups 21, 22 and 23, respectively.

The supply of air to each of the chamber portions 27, 28 and 29 from an air box 31, which is positioned directly under the stoker 2, may be independently controlled by a plurality of damper groups 32, 33 and 34. These damper groups are respectively positioned between the side plates 8 and 9 in the lower side of the chamber portions 27, 28 and 29. The damper groups 32, 33 and 34 thus constitute a bottom wall of each of the tuyère chambers or boxes 4.

One form of damper 35, which may be used in the groups 32, 33 and 34, is illustrated in Figs. 7 and 8, comprising a substantially flat plate 36 having a width slightly less than that of the tuyère chamber 4 and a length depending upon the number of dampers to be used in each group. The upper side 37 of each damper 36 is provided with a transversely recessed portion 38 which forms a curved shoulder 39 extending downwardly from the underside 41. The end portions of the recess 38 are provided with side bearings 42 and 43 for ends 44 and 45 of a pivot pin 46. The ends 44 and 45 of the pivot pin 46 are extended beyond side edges 47 and 48 of the plate 36 into bearings 49 and 51 provided in the side plates 9 and 8, respectively.

A pair of longitudinally extending ribs 52 and 53 are mounted on the upper side 37 of the plate 36 immediately adjacent to the bearing portions 42 and 43, respectively. A similar pair of reinforcing ribs 54 and 55 are positioned directly below the ribs 52 and 53 on the underside 41 of the plate. Each of these ribs is provided with beveled portions 56 and 57 which taper off into the pivot plate 36. The underside 41 of the pivot plate 36 is provided with a rearwardly extending, angled lever arm 58, which is slotted to receive an actuating link 59 and apertured to receive a pivot pin 61, the latter also extending through the link 59 for reasons as will presently appear. The weight of the plate 36 with its lever arm 58 is such that the damper as a whole is balanced, thereby requiring a minimum operating effort.

The front damper group 32 comprises three dampers 35 which are so mounted that a front edge of one damper plate 36 overlaps a rear edge of the next adjacent plate. The front edge of the front damper plate 36 abuts against an inwardly extending flange 62 of a closure plate 63 which extends forwardly to the front edges of the steel side plates 8 and 9. Intermediate the ends thereof, the plate 63 is provided with spaced side

flanges 64, which are secured to the steel side plates 8 and 9, so that the closure plate 63 may be rigidly secured in position. In this manner, the portion of the bottom wall of the tuyère chamber 4 between the front damper plate 36 and the front edge of the side plates 8 and 9 is closed. 5

The damper plates 36 of the groups 33 and 34 are also mounted in overlapping relation. Each of these groups is provided with four dampers 35. The front edge of the front damper plate in 10 the intermediate group 33 abuts against the transverse member 24, when in the closed position of Fig. 1, while the rear edge of the rear damper plate of this group abuts against the second transverse plate 25. The rear edge of the 15 rear damper plate of the front group 32 also abuts against the cross member 24 when closed. The front and rear damper plates of the rear group 34 similarly engage the cross members 25 and 26 when in the position of Fig. 1. 20

As shown in Fig. 1, the damper groups 32, 33 and 34 of each tuyère box 4 are respectively connected to the links 59. The links 59 are connected by links 65, 66 and 67 to lever arms 68, 69 and 71 mounted on cross shafts 72, 73 and 74, respectively. The shafts 72, 73 and 74 are supported by bearings secured to the base portion of a U-shape bracket 75, legs 76 and 77 of which are bolted, or otherwise secured, to one of the steel side plates. As shown in Figs. 4 and 5, the supporting bracket 75 is provided for every third steel side plate. 30

When the stoker is of relatively large width, it is desirable to divide the control means in half, operating one-half from each side of the furnace. 35 This necessitates the dividing of the transverse damper-actuating shafts, as shown in Fig. 6, into two groups 78 and 79, the group 78 comprising shafts 81, 82 and 83, while the group 79 comprises shafts 84, 85 and 86. 40

As illustrated in Fig. 4, the shafts 81, 82 and 83 may be extended through the furnace side wall 6 to a supporting framework 89 for vertical shafts 91, 92 and 93. The horizontal shafts 81, 82 and 83 and the vertical shafts 91, 92 and 93 45 are provided with coaxing worm-and-wheel devices 94, 95 and 96, the worm in each instance being mounted on the vertical shafts. The vertical shafts 91, 92 and 93 extend upwardly through a floor 97, the shafts 91 and 93 passing through 50 legs 98 and 99 of a hollow U-shaped standard 101, while the shaft 92 passes through a central base portion thereof. Each of the vertical shafts terminates at its upper end in a hand-wheel 102.

In order that the operator may know the position of the dampers in each transverse group, indicators 103, 104 and 105 are associated with the vertical shafts 91, 92 and 93, respectively. Each indicator comprises a threaded sleeve portion 106, which is rigidly secured to the vertical shaft, and a nut portion 107 which is provided with a pointer 108 extending through a slotted plate 109 mounted on the standard 101. The arrangement is such that, when the pointers 108 are at the upper end of a slot 111 of the indicator plate 109, the dampers 35 are fully opened, but when at the bottom of the slot 111 the dampers 35 are fully closed as shown in Fig. 1. The opposite shafts 84, 85 and 86 are similarly connected to an exteriorly positioned control standard 112 60 provided with hand-wheels 113 and indicating means 114. 65

When it is desired to adjust the upper damper groups 32 in order to increase the air supplied to the tuyère chamber portions 27 from the air box 75

31, the hand-wheels associated with the shafts 81 and 84 are turned until the indicators show that the desired adjustment has been effected. If one-half only of the upper group 32 is to be 5 adjusted, then the hand-wheel associated with the proper control shaft is turned. Similarly, when it is desired to actuate the groups 33 or 34, the hand-wheels therefor are operated, and if one-half only of each of these groups is to be 10 moved, then the hand-wheels associated with the proper shafts are actuated. In this way, the air supplied to the tuyère groups 21, 22 and 23 and associated fuel portions 17, 18 and 19, respectively, may be independently adjusted and a flexibility of air control obtained which results in highly efficient combustion conditions in the furnace.

It is apparent that various changes and modifications may be made in the herein-described devices, without departing from the spirit of my 20 invention and I desire, therefore, that only such limitations shall be imposed thereon as are demanded by the prior art.

I claim:

1. A stoker comprising a plurality of flat beams 25 arranged in spaced vertical planes to define the sides of alternate tuyère and retort chambers, tuyère elements supported on said beams and bridging the tops of the tuyère chambers, an air supply chamber at the bottoms of said tuyère 30 chambers, a plurality of damper elements adjustably mounted at the lower edges of said beams and the bottoms of the tuyère chambers and extending in substantially continuous series the entire length of the latter, said series of damper elements being divided longitudinally into a plurality of groups, and means for independently actuating the dampers of certain of said groups independently of the dampers of other groups.

2. A stoker comprising a plurality of flat 40 beams arranged in spaced vertical planes to define the sides of alternate tuyère and retort chambers, tuyère elements supported on said beams and bridging the tops of the tuyère chambers, an air supply chamber at the bottoms of said tuyère 45 chambers, partitions dividing said tuyère chambers transversely into a plurality of compartments, and a plurality of damper elements adjustably mounted at the lower edges of said beams and the bottoms of the tuyère chambers 50 and extending in continuous series the entire length of each of said compartments, and means for adjusting the dampers of certain of said compartments independently of the dampers of other compartments.

3. A stoker comprising a plurality of flat beams arranged in spaced vertical planes to define the sides of alternate tuyère and retort chambers, said tuyère chambers being of substantially uniform 55 depth throughout, tuyère elements supported on said beams and bridging the tops of the tuyère chambers, an air supply chamber at the bottoms of said tuyère chambers, partitions dividing said tuyère chambers transversely into a plurality of compartments and a plurality of dampers for each compartment pivotally mounted at the lower edges of said beams and the bottoms of said tuyère chambers and extending in substantially continuous series the entire length of the latter, 60 the individual dampers being relatively small in the radial dimension as compared with the depth of the tuyère chambers, whereby when the dampers of any compartment are open, the flow of air to the tuyère elements controlled by said dampers is substantially uniform throughout the length 65

of the compartment regardless of the extent of opening of the said dampers.

4. In a furnace, a stoker comprising a plurality of flat beams arranged in spaced vertical planes to define the sides of alternate tuyère and retort chambers, tuyère elements supported on said beams and bridging the tops of the tuyère chambers, an air supply chamber at the bottoms of said tuyère chambers, partitions dividing each tuyère chamber transversely into a plurality of corresponding compartments, a plurality of dampers for each compartment adjustably mounted at the lower edges of said beams and at the bottoms of the respective tuyère chambers and extending in substantially continuous series the entire length 10 of the latter, said dampers when closed overlapping to form a substantially solid partition separating the tuyère chambers from the air supply chamber, and said dampers being relatively small and affording when open a multiplicity of substantially uniformly spaced openings extending longitudinally of the individual tuyère chambers, a plurality of shafts extending transversely below said tuyère chambers and projecting through a side wall of said furnace, arms on each of said 15 shafts, links operatively connecting the arms of each shaft with the dampers of each corresponding compartment of the plurality of tuyère chambers, and means at the projecting ends of said shafts for rocking each of said shafts independently of the others.

5. An underfeed stoker comprising spaced walls defining parallel retorts, a row of tuyère blocks spanning the space between each pair of adjacent retort walls and extending lengthwise of the retorts, means forming separate air passages to localized groups of the tuyères in each row, and a separate regulatable control device for each of said groups so that the air pressure to one of said groups may be regulated independently of that to another of the groups in the same row.

6. An underfeed stoker comprising spaced walls forming parallel retorts, a row of tuyère blocks spanning the space between each pair of adjacent retort walls and extending lengthwise of the retorts, walls forming separate air passages to localize groups of tuyères in each row, a damper to regulate the air flow in each passage independently of other passages in the same row, and connections to operate together those dampers which control the air flow to tuyère groups arranged laterally of each other, thereby forming air zones which extend at right angles to the retorts.

7. An underfeed stoker comprising spaced walls defining retorts, a row of tuyère blocks spanning the space between the walls of adjacent retorts and extending lengthwise thereof, means forming a chamber for air under pressure beneath said retorts, means forming separate air passages between adjacent retort walls leading from said air chamber to localized groups of tuyère blocks, means adjacent to one of said passages to control the air pressure therein independently of the air pressure in another of said passages in the same row, and means for operating said control means from a point outside of said air chamber.

8. An underfeed stoker comprising walls forming spaced parallel retorts, rows of tuyère blocks mounted on said walls between the retorts and extending lengthwise thereof, means forming a chamber for air under pressure beneath said retorts, means forming independent air passages between adjacent retort walls leading from said chamber to localized groups of tuyère blocks in each row, a damper mounted adjacent to each 70 75

of said passages to control the air flow there-through, and means for controlling the position of one of said dampers from a point outside of said air chamber independently of another of 5 said dampers which is connected with tuyère blocks in the same row.

9. A stoker comprising a plurality of beams arranged in spaced vertical planes to define the sides of a plurality of alternate tuyère and retort chambers extending from side to side of the furnace; tuyère elements supported on said beams and bridging the tops of the tuyère chambers; an air supply chamber communicating with said tuyère chambers; partitions dividing the tuyère chambers transversely into a plurality of compartments; damper means for each of said compartments for controlling the passage of air thereto from said supply chamber; means for actuating the damper means of any of the compartments independently of the damper means of the other compartments of the same tuyère chamber, said means comprising a plurality of operating elements for the damper means of the tuyère chambers adjacent one side of the furnace and 10 operatively connected respectively with the damper means of each corresponding compartment of each of the said tuyère chambers adjacent that side of the furnace, and a plurality of operating elements for the damper means of 15 the tuyère chambers adjacent the opposite side of the furnace and operatively connected respectively with the damper means of each corresponding compartment of each of the said tuyère chambers adjacent that side of the furnace; and means 20 operatively connected with the respective operating elements at opposite sides of the furnace for independently operating the damper means of 25 the tuyère chambers adjacent one side of said 30

furnace independently of the damper means of the tuyère chambers at the opposite side of said furnace.

10. A stoker comprising a plurality of beams arranged in spaced vertical planes to define the sides of a plurality of alternate tuyère and retort chambers extending from side to side of the furnace; tuyère elements supported on said beams and bridging the tops of the tuyère chambers; an air supply chamber at the bottoms of said tuyère chambers; partitions dividing the tuyère chambers transversely into a plurality of compartments; a plurality of dampers adjustably mounted on said beams for controlling passage of air from said supply chamber to said tuyère chambers; and means for independently actuating as a group the dampers associated with each transverse row of compartments of the respective tuyère chambers, said means comprising a plurality of shafts extending transversely of the furnace below the tuyère chambers adjacent one side of the furnace and operatively connected respectively with corresponding groups of dampers of the tuyère chambers adjacent that side of the furnace, and a plurality of shafts extending transversely of the furnace below the tuyère chambers adjacent the opposite side of the furnace and operatively connected respectively with corresponding groups of dampers of the tuyère chambers adjacent that side of the furnace; and means operatively connected with the shafts at opposite sides of the furnace for independently operating the dampers of the tuyère chambers adjacent one side of the furnace independently of the operation of the dampers of the tuyère chambers at the opposite 35 side of the furnace.

HERBERT E. PRESTON.
